Primary Examiner — Michael A Pratt(74) *Attorney, Agent, or Firm* — Neugeboren O'Dowd PC(57) **CLAIM**

The ornamental design for the weapon handguard, as shown and described.

DESCRIPTION

FIG. 1 is a front perspective view of the weapon handguard; FIG. 2 is an exploded perspective view of the weapon handguard showing the handguard body, mounting adapter and barrel nut of the weapon handguard; FIG. 3 is a top view of a handguard body of the weapon handguard; FIG. 4 is a first perspective view of a handguard body of the weapon handguard; FIG. 5 is a second perspective view of a handguard body of the weapon handguard; FIG. 6 is a section view of a handguard body of the weapon handguard taken along line 6-6 of FIG. 7; and, FIG. 7 is an end view of a handguard body of the weapon handguard. The weapon shown in broken lines in FIGS. 1 and 2 is for illustrative purposes only and forms no part of the claimed design.
